CLAIM

The ornamental design for a toilet rim block holder, as shown and described.

DESCRIPTION

FIG. 1 is a top, front, left perspective view of a toilet rim block holder showing our new design;

FIG. 2 is a front view thereof;

FIG. 3 is a rear view thereof;

FIG. 4 is a right side view thereof;

FIG. 5 is a top view thereof; and,

FIG. 6 is a bottom view thereof.

The broken lines immediately adjacent to the shaded area represent unclaimed boundaries of the design. The unshaded regions within the shaded area form no part of the claimed design. The broken lines showing the remainder of the toilet rim block holder are for environmental purposes only and form no part of the claimed design. The ends of the toilet rim block holder are shown broken and bound by brackets to indicate an indeterminate length.
